US00D525291S

(12) **United States Design Patent** (10) Patent No.: **US D525,291 S**
Fukumura et al. (45) Date of Patent: ** Jul. 18, 2006

(54) **DOCUMENT FEEDER**

(75) Inventors: **Atsushi Fukumura**, Kyoto (JP);
Toshihiro Kawamura, Kyoto (JP);
Kouichi Motoyoshi, Kyoto (JP)

(73) Assignee: **Murata Kikai Kabushiki Kaisha**,
Kyoto (JP)

(**) Term: **14 Years**

(21) Appl. No.: **29/212,737**

(22) Filed: **Sep. 7, 2004**

(30) **Foreign Application Priority Data**

Mar. 15, 2004 (JP) 2004-007632

(51) **LOC (8) Cl.** **18-99**

(52) **U.S. Cl.** **D18/49**
